UNITED STATES PATENT OFFICE.

EDWARD W. LINDQUIST, OF CHICAGO, ILLINOIS, ASSIGNOR TO RALPH BAGGALY, OF PITTSBURG, PENNSYLVANIA.

APPARATUS FOR CHARGING FURNACES.

No. 805,787.

Specification of Letters Patent.

Patented Nov. 28, 1905.

Application filed March 16, 1903. Serial No. 147,974.

To all whom it may concern:

Be it known that I, EDWARD W. LINDQUIST, of Chicago, Cook county, Illinois, have invented a new and useful Apparatus for Charging Furnaces, of which the following is a full, clear, and exact description, reference being had to the accompanying drawings, forming part of this specification, in which—

Figure 1 shows in elevation, partly in section, a charging-machine constructed in accordance with my invention. Fig. 2 is a side elevation thereof, partly in vertical central section. Fig. 3 is a plan view of a modified construction. Fig. 4 is a side elevation of Fig. 3; and Fig. 5 is a plan view, on a smaller scale, of a modified construction of spout for the conveyer.

In order to secure the best results in the operation of copper-smelting furnaces, it is necessary that the charge should be supplied to the furnace at a proper rate and evenly mixed or evenly stratified. Too rapid charging is apt to chill the furnace and cause it to work irregularly, and if large amounts are added at a time the shock of the falling material is severe and is apt to cause injury to the furnace structure and pack the charge in the furnace. Many attempts have been made to provide such furnaces with charging-machines; but, so far as I am aware, these machines have not given satisfactory results, and the method ordinarily employed has continued to be the slow and expensive operation of feeding the charge by hand, a shovelful at a time. Such work is laborious and very expensive, and as it depends upon the intelligence of the workmen it is often imperfect and produces irregular working of the furnace. My invention overcomes these defects and provides a charging-machine which is simple in its construction and will operate reliably and with certainty, so that a more efficient distribution of the charge is secured and the cost of labor is very materially reduced.

The invention is of especial importance when used with furnaces which smelt rapidly and require a large supply of ore and flux.

In Figs. 1 and 2 I show the apparatus arranged in connection with a series of bins 22, having gates 23, from which the components of the charge are delivered upon conveyers 3, composed, preferably, of endless belts

passing around pulleys 4. These bins contain the several components of the furnace charge. One bin may contain copper ore, another silica, another iron ore, and another coke, and in front of each is a hopper 5, which is supported upon the beams 6 of weighing-scales, so that a measured quantity of material may be received in the hopper and thence discharged upon the conveyer 3, which runs beneath the spout of the hopper. Each hopper for this purpose is fitted with a gate 7.

In practice the person in charge of the furnace knowing the proportions of ore, flux, and coke which are desired sets the scale of each hopper so that it will balance at the weight proper for the particular material contained in the bin, and the workman having delivered such weight into the hoppers opens the gates 7 and causes the material to discharge upon the conveyer. These conveyers 3 discharge into a hopper 8, the orifice of which is preferably provided with a feeding device 9, which may be a corrugated roller, a feeding-disk, or other suitable appliance and which being driven at the desired speed delivers the material upon a conveyer 10, likewise, preferably, an endless belt passing over rollers and leading to a spout 11 over the apron 12 of the furnace 13. The conveyer 10 and the pulleys 14, over which it passes, are mounted on a frame 15, which is pivoted, preferably near its rear end, on a pivot 16, so that its front end, which is preferably supported by wheels 17 on a curved track 18, is oscillatory along the charging hopper or apron 12.

In Fig. 3 I show suitable means for effecting the oscillation or back-and-forth movement of the frame. It consists of a crank 19, connected with the frame by a pitman 20 and rotated by a worm-wheel 21, driven by a worm 22, the operation of which causes the front end of the conveyer to travel back and forth slowly along the line of the feed hopper or apron. Other means may be employed for effecting the lateral motion of the conveyer, and, if desired, it may be a bodily motion instead of an oscillatory motion.

The operation of the device is as follows: The material to be fed to the furnace is delivered upon the conveyers 3 from the weighing-hoppers in determined amounts and is discharged into the hopper 8, from which the feed-roll 9 delivers it at the desired rate upon

the conveyer 10. The motion of this conveyer carries the charge toward the furnace and discharges it onto the apron 12, whence it passes into the furnace, and as the conveyer travels back and forth at a regular speed it distributes the charge evenly from end to end of the furnace-shaft in a manner calculated to produce the most satisfactory results in the smelting operation. The whole device can be operated by one man, who by regulating the passage of the charge upon the conveyer 10 can control perfectly the rate at which the furnace is charged. The conveyer 10 is preferably inclined upwardly, so that the hoppers 5 may be near the level of the charging-platform, and, if desired, its inclination may be increased, so that it will be, in effect, an elevator and may be fitted with the usual buckets. By placing at the delivery end of the conveyer a distributing-hopper which moves back and forth along the furnace-apron the conveyer itself may be supported on a stationary frame, as shown in Fig. 5.

In Figs. 3 and 4 I show a modification of my invention, in which instead of discharging the material into the hopper 8 by the cross-conveyers 33 it is delivered thereinto from a weighing-hopper 23, which is supported by scale-beams 24 and receives its charge from wheelbarrows or in any other suitable way, the weighing-hopper being controlled by a gate 25, operated by a lever 26.

Within the scope of my invention as defined in the claims the apparatus may be modified in various ways, since

What I claim is—

1. Furnace-charging apparatus comprising in combination with a furnace having a charging-opening, a traveling conveyer discharging into said opening, and means for moving said conveyer along the opening to distribute the charge; substantially as described.

2. Furnace-charging apparatus comprising in combination with a furnace having a charging-opening, a traveling conveyer discharging into said opening, said conveyer being pivoted, and means for oscillating it on its pivot to distribute the charge; substantially as described.

3. Furnace-charging apparatus comprising a feeding device discharging into the opening of a furnace, means for moving said device along the opening to distribute the charge, and means for delivering the charge at a regu-

lated rate to the feeding device; substantially as described.

4. Furnace-charging apparatus comprising a feeding device discharging into the opening of a furnace, means for moving said device along the opening to distribute the charge, and a feed-roller adapted to deliver the charge to the feeding device; substantially as described.

5. Furnace-charging apparatus comprising a traveling conveyer discharging into the feed-opening of the furnace, means for moving said conveyer along the opening to distribute the charge, and a supplementary conveyer arranged to receive the ingredients of the charge from bins and to deliver it to the movable conveyer; substantially as described.

6. Furnace-charging apparatus comprising a traveling conveyer, means for delivering the charge thereto at a regulated rate, and means for moving the delivery end of the conveyer along the furnace; substantially as described.

7. Furnace-charging apparatus comprising in combination with a furnace weighing-hoppers supported by scales, means for delivering into the several hoppers the materials which constitute the components of the charge, and a continuously-operating, distributing-feeder by which the weighed charge is conveyed to and distributed in the furnace; substantially as described.

8. Furnace-charging apparatus comprising weighing-hoppers supported by scales, means for delivering into the several hoppers the materials which constitute the components of the charge, a common hopper into which the material from the weighing-hoppers is delivered, and a feeding device leading therefrom to the furnace; substantially as described.

9. The combination with a furnace having a charging-opening, of a suitable charger adapted to travel to and fro along said opening, said charger comprising a traveling carriage and an independently-actuated conveyer, and means for permitting the discharge of the material from the conveyer into the furnace for any position of the carriage; substantially as described.

In testimony whereof I have hereunto set my hand.

EDWARD W. LINDQUIST.
